(57) **CLAIM**

The ornamental design for a delaminator, as shown and described.

DESCRIPTION

FIG. 1 is a bottom and right perspective view of the delaminator of the instant invention;

FIG. 2 is a left side view thereof;

FIG. 3 is a top view thereof;

FIG. 4 is a bottom view thereof;

FIG. 5 is a right side view thereof;

FIG. 6 is a front end view thereof;

FIG. 7 is a rear end view thereof; and,

FIG. 8 is an enlarged top partial perspective view of the blade portion thereof, with the dashed lines showing the boundary of the figure and forms no part of the claimed design.
